DESIGN FOR A SUIT ENSEMBLE

Abraham Gruber, New York, N. Y.

Application July 2, 1940, Serial No. 93,386

Term of patent 3½ years

To all whom it may concern:

Be it known that I, Abraham Gruber, a citizen of the United States of America, residing in New York city, county of New York, and State of New York, have invented a new, original, and ornamental Design for a Suit Ensemble, of which the following is a specification, reference being had to the accompanying drawing, forming part thereof, wherein,

I claim:

The ornamental design for a suit ensemble, as shown.

ABRAHAM GRUBER,
